United States Patent Office.

JAMES SIMPSON, OF ST. LOUIS, MISSOURI.

Letters Patent No. 73,843, dated January 28, 1868.

IMPROVED BRICK-MACHINE.

The Schedule referred to in these Letters Patent and making part of the same.

TO ALL WHOM IT MAY CONCERN:

Be it known that I, JAMES SIMPSON, of St. Louis, in the county of St. Louis, and State of Missouri, have invented a new and useful Improvement in Brick-Machine; and I do hereby declare that the following is a full, clear, and exact description thereof, which will enable those skilled in the art to make and use the same, reference being had to the accompanying drawings, forming part of this specification.

The object of this invention is to construct a cheap and simple machine, by which compressed brick may be manufactured in a perfect and expeditious manner; and the invention consists in operating two compressers by cranks, which are revolved by a main shaft, and in other devices connected therewith, as will be more fully described hereinafter.

Figure 1 is a longitudinal sectional side view of the machine, the section being through the line *yy* of fig. 2.

Figure 2 is a top or plan view, and

Figure 3 is a vertical cross-section through the line *xx* of fig. 1.

Similar letters of reference indicate corresponding parts.

The parts of the machine are supported on a substantial frame which is marked A in the drawing. B indicates longitudinal timbers, which rest upon the frame A, and which form ways or guides for the cross-heads, which are attached to the compressers. C is the main crank-shaft. Upon the outside of the frame, on each end of this shaft, there are crank-wheels marked D and E. *aa* indicate the crank-pins or wrists on these wheels. F and G are the two compressers. G is operated by a pitman marked *e*, which is attached to a crank formed on the shaft C, between the wheels E D, as seen more distinctly in fig. 2. The compressor F is operated by two pitmen *f* and *g*, which are attached to a cross-head, *h*, at the outer end of the compressor, and to the wrist-pins *aa* on the wheels E D, at the other end. J is a clay-chamber. *i* is the bottom of the brick-chamber. *m* is the aperture in the bottom, through which the compressed brick are delivered. *n* is an adjustable plate, by which the quantity of clay delivered into the brick-chamber is regulated. It is adjustable by the screw *o*. The compressers F and G are worked respectively by their pitmen, as mentioned above, attached to their cranks, which cranks are so placed with regard to each other, that when the compressers are at the beginning of a stroke, (that is, when they are farthest away from the shaft C,) they may be sufficiently far apart to allow enough clay to lie between them to form a brick. The cranks are also so placed that while the compressers are underneath the plate *n*, and before arriving at the aperture *m*, they may approach each other as near as is required for the breadth of the brick. The length of the brick is determined by the breadth of the brick-chamber, and its thickness by the thickness of the compressers. From this point to the end of the stroke, they separate from each other sufficiently to allow the brick thus formed to fall out through the aperture *m*. The sides of the clay-chamber form grooves for the compressers to slide in. P is an arm, which is attached to the frame at one end, as seen in the drawing. It is raised and lowered so that its end *r* receives the brick, (which drops through the aperture *m*,) and deposits it on to a revolving apron, carrying-board, or other means of conveyance. S is an arm, which is attached to P, and *t* is a rod, which is attached to S and to the cross-head *h*, as seen in fig. 1. This arm S and rod *t* thus attached operate the arm P.

The operation of the machine is as follows: At the beginning of the stroke, the space between the ends of the compressers is filled with clay, which, of course, will be more than enough to form a brick. As the compressers gradually approach each other, all the superfluous clay will be forced up again into the clay-chamber J, till the end of the compressor F reaches the plate *n*. All the clay now contained in the brick-chamber, (or between the ends of the compressers,) is forced into the space, (shown in red,) between them, as seen in the drawing, the compressers still travelling in the same direction, and separating over the aperture *m*.

Having thus described my invention, I claim as new, and desire to secure by Letters Patent—

1. The combination of the pivoted arm P, having receiving-plate *r*, bar S, and rod *t*, with the cross-head *h*, compressors F G, and opening *m* in the bottom plate *i*, as herein described for the purpose specified.
2. The plate *n* and screw *o*, in combination with the hopper J and compressors F G, as herein described for the purpose specified.
